APPARATUS FOR THE MANUFACTURE OF
ARTIFICIAL SILKWillem Bakker, Arnhem, Netherlands, assignor to
American Enka Corporation, Enka, N. C., a cor-
poration of DelawareApplication October 15, 1937, Serial No. 169,317
In Germany October 30, 1936

4 Claims. (Cl. 242—43)

The present invention relates to an apparatus for the manufacture of artificial silk and more particularly to a traversing mechanism for shortening the stroke of the thread guide on artificial silk spinning machines.

In winding bodies of artificial materials, and more particularly rayon threads, on bobbins or spools, a traversing mechanism is employed to control the reciprocation of the thread guide adjacent the rotating bobbin. By means of suitable gearing, linkage or other mechanism the stroke of the thread guide is gradually shortened throughout the period of winding, resulting in the production of a wound package having tapered or conical ends.

It is an important object of the present invention to provide an improved form of traversing mechanism of the above character. More particularly the invention contemplates the provision of a traversing mechanism including a swinging rod carrying the thread guide mechanism, which may include the usual heart-shaped cam and roller for imparting swinging movement to the thread guide rod, and control means including an oscillatable member operated in synchronism with the rotating shaft upon which the bobbin is mounted for shortening the stroke or amplitude of swinging movement of the thread guide throughout the winding operation. In the preferred form of this invention the control means is advantageously actuated from the same variable speed mechanism as is employed for compensating for the increasing diameter of the bobbin during winding.

Another object of my invention is to provide a traversing mechanism of the above character which is simple in construction and operation and which may be readily incorporated in well known types of artificial silk spinning machines without requiring any substantial alteration of their structure.

Other objects and advantages will become apparent from the following detailed description of a preferred embodiment of the invention, when considered in connection with the accompanying drawings, wherein:

Figure 1 is a view, in part sectional, of an artificial silk spinning machine and indicating somewhat diagrammatically with respect thereto the arrangement of the thread guide and its traversing mechanism including the control means for shortening the stroke of the thread guide during winding;

Figure 2 is a plan view of the traversing mech-

anism and the mechanism for actuating the control means in the position it occupies at the beginning of the winding operation; and

Figure 3 is a plan view similar to that of Figure 2, but showing the position of the mechanism for actuating the control means at the conclusion of the winding operation.

Referring in detail to the drawings, in Figure 1 is shown the frame 1 of a spinning machine with which is associated a candle filter 2 suitably connected to pipe lines (not shown) for supplying a spinning solution to the candle filter. The spinning solution is forced through the candle filter and a spinneret 3 connected thereto into a precipitating bath 4. The newly formed thread 5 extends upwardly and is wound upon a bobbin 6 mounted on one end of a horizontally disposed rotating shaft 7. The shaft 7 is driven in any suitable manner, as by means of a worm 8 meshing with a worm wheel 9 fastened to the shaft 7.

In order to permit proper washing of the artificial silk thread after it has been collected upon the bobbin, it is necessary to impart a crosswise displacement to the thread as it is wound upon the bobbin. Such displacement is effected by the provision of a traversing mechanism including a thread guide 9, through which the thread passes in winding onto the bobbin and being carried upon the end of a thread guide rod 10 connected to and depending from a pendulum shaft 11 journaled in a bearing 12. The pendulum shaft is rockable in bearing 12 so as to impart a forward and backward stroke to the thread guide which is located adjacent the bobbin. Rocking movement is imparted to the pendulum shaft through the chain of linkage comprising a lever 13 having one end fastened to the pendulum shaft and a link 14 pivotally connecting the other end of lever 13 with a slidable rod 15. The slidable rod is supported in a rectangular box member 16 mounted for oscillatory movement about a horizontal axis upon a pair of hollow trunnions 17 supported in bearings 18. The box member 16 is oscillated by means of an arm 19 connected at one end to the box member and carrying at its other end a roller 20 designed to ride upon the periphery of a heart-shaped cam 21 eccentrically mounted upon a shaft 22 which is continuously driven at uniform speed. The lever 13, link 14 and slidable rod 15 form movable parts of a parallelogram through which oscillation of the box member 16 is transmitted to the pendulum shaft 11 and consequently to the thread guide rod 10.

The position of the linkage at opposite ends of

a full stroke imparted by the heart-shaped cam 21 is shown in full and dotted lines in Figure 1.

Referring more particularly to Figures 2 and 3, within the box member 16 is a rectangular block 23 having limited sliding movement longitudinally thereof. To one end of the block is affixed a pin 24 which extends outwardly through one of the hollow trunnions 17. A flexible cable 25 is fastened to the outer end of the pin 24 and 10 this cable extends over a pulley 26 and is provided with a weight 27 tending to draw the block 23 to the right as indicated in the figures. The block is provided with an inclined cam slot 28 sloping downwardly from left to right and 15 slidingly received within this slot is a pin 29 fastened to and extending laterally from the slide rod 15. The slide rod 15 passes through aligned openings having necks 30 formed in opposite sides of the box member and through a suitably 20 provided longitudinal slot in the slide block so as to intersect the axis of oscillation of the box member. A pin 31 secured to the end of slide block 23 opposite its end carrying the pin 24 extends outwardly through the adjacent hollow 25 trunnion 17 of the box member and is connected by a flexible cable 32 to one end of an actuator lever 33 which is intermediately pivoted at 34.

The box member 16 and slide block 23 form components of the control means for the traversing mechanism just described, which means are operatively connected to and actuated from the compensating mechanism which drives shaft 7 upon which the bobbin is mounted. This compensating mechanism comprises a pair of driving 35 and driven cones 35 and 36, respectively, splined upon parallel shafts 35a and 36a, respectively, and connected by a belt 37. The shaft carrying the driving cone is operated from a suitable source of power, not shown (which may be the 40 same source of power as that which rotates shaft 22 carrying the heart-shaped cam 21), and the shaft upon which the driven cone is mounted is connected through a suitable transmission, not shown, to a shaft carrying the worm 8, which 45 latter imparts motion through worm wheel 9 to shaft 7 carrying the bobbin 6.

Supported for rotation above and intermediate the cones 35 and 36 is a screw-threaded shaft 38 upon which a nut 39 suitably held against rotation is adapted to travel. The screw-threaded shaft is driven from the same source of power which is employed for rotating the driving cone and the nut 39 is so fashioned as to engage and serve as a shifter for the belt 37. The end of 55 the actuator lever 33 opposite to its end which is connected by the flexible cable 32 to the pin 31 extends adjacent the nut 39 and is provided with a roller 40 which, under the urge of the weight 27, bears upon the flat end face of the nut. As 60 the nut travels along the screw-threaded shaft 38, shifting the belt 37 to the right, the actuator lever will be swung from the position shown in Figure 2, corresponding to its location at the beginning of a winding operation, to the position 65 shown in Figure 3, at the conclusion of the winding period.

The operation of the traversing mechanism described above results in the winding of the thread upon the bobbin in the manner indicated 70 by dotted lines in Figure 1 so as to produce a package having conical ends. As will be apparent from the preceding description, as the thread 5 passes from the spinneret 3 up through the thread guide 9 it will be evenly laid down upon 75 the rotating bobbin through the reciprocation

of thread guide rod 10 which receives its motion from the heart-shaped cam 21 through the linkage comprising arm 19, box member 16, slide rod 15, link 14, lever 13 and pendulum shaft 11. As the thread builds up upon the bobbin the rotary speed thereof must be continuously reduced to compensate for the increasing diameter of the thread package in view of the constant rate of supply of the thread by the spinneret 3. This is accomplished by means of the variable speed 10 driving mechanism represented by the cones 35 and 36 and connecting belt 37 indicated in Figures 2 and 3. In order to control the winding of the thread so as to produce a thread package having conical ends, the full stroke movement 15 normally imparted to the thread guide through rotation of the heart-shaped cam must be gradually shortened throughout the winding interval. This is accomplished by the control means including the slide block 23 and the actuator 20 lever 33. As the belt shifting nut 39 slowly moves to the right (Figures 2 and 3), the actuator lever, which is yieldably held in contact with the nut under the urge of weight 27, pulls the slide block to the left, it being understood that the 25 slide block while free to slide within the box member is non-rotatable with respect thereto. This causes the pin 29 extending through the inclined cam slot 28 in the slide block to gradually move downwardly, that is, in a direction 30 such as to retract the slide rod 15 and shortening the length of the lever arm of the slide rod measured from the axis of rotation of the box member upon its trunnions 17 to the point of pivotal connection of the slide rod with link 35 14. Since the throw or arc of swing of the end of the slide rod is thus constantly and gradually diminished, the motion imparted to the thread guide rod 10 will be correspondingly decreased, thus shortening the stroke of the thread guide 9. 40

It will be readily apparent that various changes in arrangement and design may be made in the traversing mechanism described above without departing from the spirit of the invention. For example, instead of employing a straight slot as 45 indicated in the preferred form of the invention described above, in which the stroke of the thread guide is uniformly decreased throughout the winding period, a curved or an angular slot may be substituted to vary the rate of decrease of 50 the stroke, as for example to more slowly shorten the stroke at the beginning of the winding period. Also other means than those shown for imparting movement to the box member may be adopted. 55

An important advantage of the invention resides in the adaptability of the control means to artificial silk spinning machines now in common use, since it is unnecessary to change the construction or arrangement of the heart-shaped 60 cam relative to its driving mechanism. Moreover, substantially the same linkage as is now generally employed in such spinning machines for actuating the thread guide may be preserved. 65

What I claim is:

1. A winding mechanism for artificial silk thread and the like comprising a bobbin, means for operating the bobbin at variable speed, a thread guide arranged adjacent the bobbin, means for effecting an oscillatory movement of 70 the thread guide along the axis of the bobbin, means for gradually reducing the stroke of said oscillatory movement including a box mounted for oscillation about an axis, said thread guide oscillating means being also operable to oscillate 75

- said box, linkage connected to the thread guide having a slidable rod connected to its other end and said rod being oscillatable with said box about the same axis as the box, a cam member 5 mounted within the box for longitudinal movement along the axis of oscillation thereof, means on said slidable rod coacting with the cam member and movable transversely with respect to the box, said means acting to vary the distance between the connection of said linkage to said rod and the axis of oscillation of said rod according to the length of stroke desired to be imparted to the thread guide, and means for moving said cam member longitudinally with respect to the box, 10 15 said means being associated with the bobbin operating means whereby variation in the speed of rotation of the bobbin and variation in the length of stroke of the thread guide may be effected simultaneously.
- 20 2. A winding mechanism for artificial silk thread and the like comprising a bobbin, means for operating the bobbin at variable speed, a thread guide arranged adjacent the bobbin, means for effecting an oscillatory movement of the thread guide along the axis of the bobbin, means for gradually reducing the stroke of said oscillatory movement including a member mounted for oscillation about an axis, said thread guide oscillating means being also operable to oscillate 25 said member, linkage connected to the thread guide having a slidable rod connected to its other end and said rod being oscillatable with said member about the same axis as that of the member, a cam mounted for movement along the 30 axis of oscillation of the member, means on said slidable rod coacting with the cam and movable transversely with respect to the member, said means acting to vary the distance between the connection of said linkage to said rod and the axis of oscillation of said rod according to the 35 length of stroke desired to be imparted to the thread guide, and means for moving said cam longitudinally with respect to the member, said means being associated with the bobbin operating 40 45 means whereby the speed of rotation of the bobbin and the length of stroke of the thread guide may be varied simultaneously.
3. A winding mechanism for artificial silk thread and the like comprising a bobbin, means
- for operating the bobbin, means for varying the speed thereof, a thread guide arranged adjacent the bobbin, means for effecting an oscillatory movement of the thread guide with respect to the axis of the bobbin including a composite lever 5 arranged to be extended and contracted, said composite lever being formed of two relatively movable parallel sections one of which is connected to the thread guide, a mounting for supporting the composite lever for oscillatory movement, means for relatively moving the sections of the composite lever for gradually changing the effective length thereof and resultantly to effect a gradual reduction of the stroke of the thread guide across the bobbin, said means for relatively 10 moving said sections being propelled by the bobbin operating speed varying means whereby the speed of rotation of the bobbin and the length of stroke of the thread guide are varied simultaneously.
- 20 4. A winding mechanism for artificial silk thread and the like comprising a bobbin, a bobbin driving and speed change mechanism including a belt shifting means for driving the bobbin at varying speeds, a thread guide arranged adjacent the bobbin for directing the thread onto the same, means for operating the thread guide and for gradually changing the length of the stroke thereof including an oscillatory member, means for oscillating said oscillatory member, a 25 30 slidable rod having one end connected with the thread guide, said rod being mounted for oscillation with and for sliding lateral movement with respect to the oscillatory member, a cam member mounted within the oscillatory member, means on said slidable rod coacting with the cam member so that movement of the cam member causes sliding movement of the slidable rod to cause that end of the slidable rod which is connected with the thread guide to move toward the 35 oscillatory member, and means actuated by the belt shifting means for automatically so moving the cam member and thereby effecting the moving of the slidable rod with the resultant shortening of the stroke of the thread guide, said means 40 45 actuated by the belt shifting means comprising a pivoted lever connected with the cam member and with the belt shifting means.

WILLEM BAKKER.
